Attnys.

UNITED STATES PATENT OFFICE.

CHARLES L. HOPKINS, OF RIVER FOREST, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL-FIXTURE-SUPPORTING DEVICE.

Application filed May 20, 1921. Serial No. 471,108.

My invention relates to electrical fixture supporting devices, and connections therefor.

One of the objects of my invention is to provide an improved fixture supporting device in which the fixture can be readily connected and disconnected with respect to the receptacle, both electrically and mechanically.

10 A further object of my invention is to provide such a device which will be simple in construction, cheap to manufacture and durable and efficient in use.

15 Further objects will appear from the detailed description to follow and from the appended claims.

In the drawings in which an embodiment of my invention is shown—

Fig. 1 is a vertical transverse section showing part of a fixture and its connecting bracket and support;

Fig. 2 is a rear elevational view of the connecting bracket and plug-in device;

Fig. 3 is a face view of the receptacle; and

25 Fig. 4 is a section on the line 4—4 of Fig. 2.

The construction shown in the drawings comprises a fixture 12, (the stem alone being shown) a receptacle 13, a plug-in device 14 for electrically connecting the fixture with the receptacle 13, and a mechanical connecting member which in the embodiment shown is in the form of a bracket 15 for mechanically connecting the fixture with 30 respect to the receptacle.

The plug-in device 14 is carried by the connecting bracket 15, being bodily slidably mounted thereon, to permit the necessary movement of the connecting bracket 15 for 35 making the mechanical connection without interfering with the insertion of the contact blades 16 of the plug-in device 14 into the opening 17 provided in the receptacle 13.

The mechanical connector member 15 is 40 secured to a supporting plate 18 (which may be a sort of cover for the outlet box) by means of four hook members 19, which hook over the edges of suitable openings in the supporting plate 18. The connection between the connecting bracket 15 and the supporting plate 18 is effected by two movements, first, a movement of insertion to bring the hook members 19 back of the plate 18, and second, a downward movement to en-

gage the hook members with the edges of 55 the opening.

The sliding connection between the plug-in device 14, and the connecting bracket 15, hereinbefore referred to, permits the downward movement of the connecting bracket 15 without interference from the engagement of the blades 16 in the opening 17. In other words, the plug-in device 14 remains stationary during the downward movement of the connecting bracket 15. This sliding connection of the plug-in device 14 with the connecting bracket 15 is effected by means of a pair of lugs 20, struck up from the material of the bracket 15, and a pair of inwardly extending portions 21 of the bracket 15, the insulating base 22 of the plug-in device lying between the lugs 20 on the one side, and the inwardly extending portions 21 on the other side. The plug-in device 14 is prevented from lateral movement with respect to the connecting bracket 15 by means of cheek-pieces 23 formed integral with the bracket, the insulating base 22 lying between these cheek-pieces. The lugs 20 may be bent down after the insulating base 22 is placed in position on the bracket. The bracket 15 may be a sheet metal stamping, the lugs 20, cheek-pieces 23 and hooks 19 being formed as integral parts of this stamping.

In order to hold the bracket 15 in connected position on the plate 18, a coil torsion spring 24 is provided, the coil portion of which surrounds a pin 25^a secured to the bracket 15, and one end of which spring bears on the said bracket as indicated at 24, and the other end of which spring bears on the plug-in device as indicated at 26. The tension of the spring 25 is such as to tend to force the bracket 15 downwardly with respect to the plug-in device 14. The effect of this spring 24 is to hold the bracket 15 in engaging position when the plug 14 is inserted in the receptacle, and the bracket is connected to the supporting plate 18.

For connecting the stem 12 of the fixture to the bracket 15 a connecting strap 27 is provided, to the intermediate portion of which is secured the bushing 28 to which the stem 12 is secured, the ends of the strap being secured to the connecting bracket by means of screws 29. A suitable ornamental finishing plate or escutcheon 30 may be secured in front of the supporting plate 18. The wires

for the fixture 12 may lead from the stem through openings 31 in the insulating base 22 to the binding screws 32 which are threaded into the contact blades 16.

5 For electrically and mechanically connecting the fixture with respect to the receptacle 13, the connecting bracket 15 and plug-in device 14, together with the fixture, are presented in position with respect to the receptacle 13, (using the stem 12 of the fixture as a sort of handle if desired) the blades 16 are pushed into openings 17 of the receptacle, and the hooks 19 are pushed into the openings in the supporting plate 18 (the bracket 15 being held upwardly against the tension of the spring 24, to bring the ends of the hooks above the lower edges of these openings). After the hooks have been pushed in far enough, the connecting bracket 15 is slipped 10 down, or is allowed to slip down to engage the hooks 19 in back of the plate 18. The spring 24 will hold the bracket 15 down in connected position.

Having thus described my invention, what 25 I claim as new and desire to secure by Letters Patent of the United States is:

1. Means for electrically connecting a fixture with respect to a receptacle, and mechanically connecting and supporting the fixture with respect to the receptacle, said means comprising a supporting plate, a connecting member, and a plug-in device mounted for bodily sliding movement on said member, said member and plate being provided with interengaging means whereby said member may be connected to said plate by movement toward said receptacle and laterally with respect thereto, and yielding means mounted on the member and acting on the plug for holding the member in connected position.

2. Means for electrically connecting a fixture with respect to a receptacle, and mechanically connecting and supporting the fixture with respect to the receptacle, said means comprising a supporting plate, a connecting member, and a plug-in device mounted for bodily sliding movement on said member, said member and plate being provided with interengaging means whereby said member may be connected to said plate by movement toward said receptacle and laterally with respect thereto, and yielding

means acting between the member and plug for holding the member in connected position.

3. Means for electrically connecting a fixture to a receptacle, and mechanically connecting and supporting the fixture with respect to the receptacle, said means comprising a supporting plate, a connecting member and a plug-in device mounted for bodily sliding movement on said member, said supporting plate having a flat apertured portion, and said member having hook members for engaging said apertures, and yielding means mounted on the member and acting on the plug for holding the member in connected position.

4. Means for supporting a fixture in position with respect to a receptacle comprising a connecting member having hooks for passing through a supporting plate and hooking in behind it, means for electrically connecting said fixture with respect to said receptacle comprising a plug having contacts for engaging the receptacle contacts slidably mounted on said connecting member whereby said hooks can be moved in behind said plate after said plug contacts have entered the receptacle, and means acting between the plug and connecting member to hold the connecting member yieldingly against upward movement to prevent the hooks from becoming disconnected from the plate.

5. Means for supporting a fixture in position with respect to a receptacle comprising a connecting member having hooks for passing through a supporting plate and hooking in behind it, means for electrically connecting said fixture with respect to said receptacle comprising a plug having contacts for engaging the receptacle contacts slidably mounted on said connecting member whereby said hooks can be moved in behind said plate after said plug contacts have entered the receptacle, and yielding means acting between the connecting member and plug and tending to force the connecting member in one direction and the plug in the opposite direction to prevent the bracket from being disconnected.

In witness whereof, I have hereunto subscribed my name.

CHARLES L. HOPKINS.
